INVENTOR.

A. B. DISS
BY *John Diss*
ATTORNEY.

UNITED STATES PATENT OFFICE.

ALBERT B. DISS, OF NEWARK, NEW JERSEY, ASSIGNOR TO THE BASSICK COMPANY, OF BRIDGEPORT, CONNECTICUT, A CORPORATION OF CONNECTICUT.

CASTER.

1,420,415.

Specification of Letters Patent. Patented June 20, 1922.

Application filed January 28, 1921. Serial No. 440,559.

To all whom it may concern:

Be it known that I, ALBERT B. DISS, a citizen of the United States, residing at the city of Newark, county of Essex, and State 5 of New Jersey, have invented certain new and useful Improvements in Casters; and I do declare the following to be a full, clear, and exact description of the invention, such as will enable others skilled in the art to 10 which it appertains to make and use the same.

This invention relates to certain new and useful improvements in casters, and the primary object thereof is to provide means for 15 holding the caster against lateral movement formed and related to the bottom end of the furniture leg so as to be concealed from view.

As is well known the furniture is made by 20 one manufacturer and the caster by another, and while attempts have been made to match up the colors of the two metals, still this has proven to be difficult and in numbers of instances has failed, consequently the objection 25 occurs of a vari-colored effect which is especially fatal in the instance of high grade and costly furniture.

A further object of the invention is to provide improved means formed separate 30 from the socket for holding the pintle in the socket to thereby eliminate the usual integral indented parts formed in the socket. These indented parts through continued withdrawal and insertion of the pintle be- 35 come flattened and lose their effectiveness, in the instance of the socket being made of soft metal and in instance of hard metal, the formation of the indentations frequently re- results in distortion of the socket.

40 In the drawings:—

Figure 1, is a vertical sectional view of the invention;

Figure 2, is a section on line 2—2 of Figure 1;

45 Figure 3, is a top plan view of the bottom plate of the caster prior to bending the spurs outwardly therefrom and

Figure 4, is a side elevation of Figure 3 with the spurs bent outwardly.

50 In proceeding in accordance with the present invention, a socket 1 is provided and secured at 2 to a bottom plate 3. Spring arms or fingers 4 of an approximately U-formation are employed which abut the inner surface of the furniture leg L, the U-

structure being secured by a rivet 5 to the top of the socket, the rivet seating on top of the head 6 of the pintle 7, thus forming a top-bearing type of caster.

The invention in one of its two aspects 60 resides in the bottom plate 3 which is of the same diameter as that of the leg bottom and which seats flat and snugly against the bottom end of the leg and flush with the periphery of the leg, so that the periphery only of 65 the plate is exposed. Thus even though dissimilarly colored metals of the leg and plate may be used, the difference is not noticeable. In order to hold the plate against lateral movement relative to the leg, upstanding 70 fins or spurs 8 are lanced from this bottom plate at a short distance from the perimeter of the latter so that when the socket member is inserted within the leg these upstanding fins or spurs will snugly engage the inner 75 circumference of the leg and thereby hold the socket member firmly as against swaying.

The upstanding fins or spurs can be lanced from the bottom plate or they might be secured thereto so as to be rigid therewith in 80 any suitable manner, it being noted that with their use there is nothing to be seen at the bottom of the furniture leg except the leg itself, the spurs being concealed within the leg as distinguished from the practice 85 of using plate attaching means exteriorly of the leg and consequently exposed.

As is apparent from Figure 1, of the drawings, the outer edges of the spurs have tight friction engagement with the inner circum- 90ference of the leg, thereby effectively securing the caster in place.

By virtue of the inverted V-formations of the spurs, it will be obvious that same are easily introduced into the leg. 95

The second aspect of the invention, resides in the provision of a freely suspended U-shaped spring member 9, the ends of which freely engage in diametrically opposed openings 10 formed in the socket 1 100 and which normally engage beneath the pintle head 6 as depicted in Figure 1, to thereby lock the pintle as against accidental withdrawal.

Usually a pair of indentations has been 105 made in opposite sides of the socket in order to accomplish this same result, but there is such a difference in the metal of a socket that these indentations would frequently distort the socket or else the metal would 110

be so soft that the constant insertion and withdrawal of the pintle would iron out the dents so that there would be nothing to hold the pintle.

5 In the present structure the U or horse-shoe shaped spring is of high grade spring quality and its extremities extend loosely through opposite holes in the socket, and when the pintle is inserted it spreads these 10 extremities slightly, the latter then recovering and locking the pintle as soon as the head of the latter has passed beyond the spring members.

15 The ends of the U-shaped spring can freely rotate when the pintle head is moved therepast, thus facilitating the operation.

20 While this invention is shown in connection with what is termed a "top bearing" caster, nevertheless the invention is not limited as to its use in connection with any particular caster since it will be clear that this 25 bottom plate will perform its function irrespective of the particular form of caster employed.

25 What is claimed is:

1. In a caster, a bottom plate of substantially the same diameter as that of the furniture leg and formed to seat against the lower

end of the leg, and spurs carried by the plate and engaged with the inner circumference 30 of the leg to be thereby concealed and to hold the plate against lateral movement relative to the leg, said spurs being of inverted V-formation so as to be wedged into engagement with the leg.

35

2. In a caster, a socket having opposed openings, a pintle having a head, and an approximately U-shaped spring having its free ends extending through the openings and extending into the socket interior so 40 as to allow the head to be moved therepast.

3. In a caster, a socket having opposed openings, a pintle having a head, and means movable in the openings and extending into the socket to allow the head to be moved 45 therepast.

4. In a caster, a socket, a pintle having a head, and spring means formed independent of the socket and extending therein to allow the head to be moved therepast.

50

In testimony whereof I affix my signature.

ALBERT B. DISS.
